UNITED STATES PATENT OFFICE.

HENRY W. SCHWARZ, OF MART, TEXAS.

CURTAIN FOR VEHICLES.

1,358,341.

Specification of Letters Patent.

Patented Nov. 9, 1920.

Application filed March 20, 1918. Serial No. 223,501.

To all whom it may concern:

Be it known that I, HENRY W. SCHWARZ, a citizen of the United States, residing at Mart, in the county of McLennan, State of Texas, have invented certain new and useful Improvements in Curtains for Vehicles; and I do hereby declare the following to be a full, clear, and exact description of the invention, such will enable others skilled in the art to which it appertains to make and use the same.

The invention relates to curtains for vehicles, and more particularly to the class of side roll curtains for foldable automobile tops or the like.

The primary object of the invention is the provision of a roll curtain of this character, and a mounting therefor, which will permit of ready raising and lowering of the curtain; and which will permit also the disposition of the curtain when rolled, in such a way as to present no interference with the folding of the vehicle top.

A further object of the invention is the provision of a curtain of this character, wherein the roller is adjustable to fit various sizes of curtains in accordance with the requirement thereof for the vehicle top, and also to permit its engagement in or disengagement from supporting brackets.

With these and other objects in view, the invention consists in the features of construction, combination and arrangement of parts as will be hereinafter fully described, illustrated in the accompanying drawings and pointed out in the claims hereunto appended.

In the accompanying drawings:

Figure 1 is a fragmentary vertical sectional view through an automobile top showing the side curtain constructed in accordance with the invention mounted in the top and extended with adjacent portions of curtains on opposite sides thereof connected thereto,

Fig. 2 is a vertical longitudinal sectional view through the casing of the curtain and the roller, the parts being partly broken away,

Fig. 3 is a fragmentary enlarged sectional view on the line 3-3 of Fig. 1,

Fig. 4 is an enlarged sectional view on the line 4-4 of Fig. 1,

Fig. 5 is a fragmentary perspective view 55 of one of the limbs of the bow for the top

showing the curtain roller brackets mounted thereon,

Fig. 6 is a vertical longitudinal sectional view through one of the latch casings for the curtain,

Fig. 7 is a transverse sectional view taken through the roller and casing therefor showing in detail the fastening of the curtain upon the roller,

Fig. 8 is a fragmentary sectional view 65 through the rod at the lower end of the curtain.

Similar reference characters indicate corresponding parts throughout the several views in the drawings.

Referring to the drawings in detail A designates generally the side roll curtain, preferably made as usual from flexible water proof material and formed at its upper end with a casing 10 in which is received a roller including the sections 11 and 12 slidably connected with each other, the section 11 being telescoped within the section 12 and in the section 11 is contained the usual winding spring for effecting the 80 automatic winding of the curtain A upon the roller when said curtain is raised. The adjustability of the sections 11 and 12 of the curtain roller permits the lengthening and shortening thereof in accordance with the 85 width of the curtain hung thereon and also provides for engagement of the roller in its support, and for disengagement therefrom, as will be later set forth. Extending longitudinally of the roller outside of 90 the casing 10 is a pair of retaining strips 13 which at their inner ends lap within an eye 14 formed on the section 12 of said roller and said eye projecting through an opening or slot 10' in the casing 10, while 95 the outer ends of these strips 13 are fastened to the sections 11 and 12 near the ends thereof through the medium of screw fasteners 15 and in this manner the curtain A is prevented from twisting on the roller. 100

Adjustably secured on the vertical arms 16 of the bows of the top at opposite ends of the roller are substantially L-shaped brackets 17, each being formed with a central opening to receive a stud 18 on each 105 arm 16 while embracing the arm is a substantially U-shaped cleat 19 which has its ends detachably fastened to the brackets 17 which is formed with opposed openings 20 on opposite sides of the center opening for 110

the stud 18 for receiving the ends of the cleat 19 and in this manner the bracket 17 can be adjusted on the arm when the occasion requires that the bracket be turned in 5 different positions in the mounting of the curtain.

On the lower end of the curtain A transversely thereof is a casing 21 in which is mounted a rod 22 which is constructed for 10 permitting the lengthening or shortening thereof and the ends of this rod project beyond the side edges of the curtain A to engage with the brackets 17 when the curtain is wound upon the roller so as to prevent excessive winding of said curtain thereon when it is raised.

Mounted on the rod 22 near opposite side edges of the curtain A are latch casings 23 having notches 24 for receiving the shanks 20 of the stationary buttons 25 mounted on the body of the vehicle and within these casings 23 are held spring pressed latch bolts 26 which are moved to retracted position through the medium of finger levers 27 25 pivoted in the casings 23, the latter being also formed with finger engaging extensions 28 to enable the convenient gripping of the lever 27 when it is desired to release the bolts 26 to free the latch casing 23 from engagement with the keeper buttons 25 when the curtain is lowered or extended to permit the automatic winding thereof upon the roller under the action of the spring therein.

On the brackets 17 are mounted hangers 35 29 and 30 respectively one of which is stationarily mounted while the other is capable of adjustment and in these brackets are engaged the trunnion ends of the roller for the curtain A for the mounting of the same in 40 the vehicle top. The adjustable hanger permits the turning thereof on the bracket so as to hang the roller and curtain when wound thereon crosswise of the top in a position at right angles to the side of said top when it is 45 desired to fold the top so that the hanging of the curtain will not interfere with the folding or unfolding of the top when lowering or raising the same. Normally the curtain is hung at the side of the vehicle top and the 50 hangers for the rollers are positioned in such position to support the roller for the curtain.

It is obvious that the engagement of the roller trunnions in the brackets and their disengagement therefrom, necessitates 55 lengthening or shortening of the roller, as the case may be; and it will be seen that this

is permitted by the telescopic connection of the roller sections. As shown in Fig. 1, the opening 10' is somewhat longer than the eye 14 longitudinally of the roller, so that when 60 the roller is shortened, the curtain is free to buckle at this point, this structure thus preventing interference of the curtain with the shortening of the roller.

Mounted on the inner face of the curtain 65 parallel with but spaced from the opposite side edges are strips 30, each being free at one edge and has mounted at intervals thereon hooks 31 while above the series of hooks and carried by the strips is a lacing cord 32 70 which is adapted to engage the hooks 31 on adjacent curtains for fastening the same together at their meeting edges.

The adjustment of the rod 22 is for the purpose of having the same fit various 75 widths of curtains, the casement 21 for said rod being cutaway to accommodate the latch casings 23 which are mounted upon the rod.

In raising and lowering the curtain A the same rolls upon and unrolls from the roller 80 under the tension of the spring therein.

It is of course to be understood that changes, variations and modifications may be made in the invention such as come properly within the scope of the appended claim, 85 without departing from the spirit of the invention or sacrificing any of its advantages.

The rod 22 is formed in sections and the section 22' has telescoped therein the other section of said rod to permit adjustment 90 thereof while the fastener 22'' secures the sections of said rod in their adjusted relation to each other.

What is claimed is:—

The combination with a roller made up of 95 sections telescoping one in the other at their inner ends, strips secured upon the sections at their outer ends and with their inner ends lapping each other, and an eye loosely receiving the lapping ends of the strips, its 100 shank being carried by one section; of a curtain having at its upper end a casing surrounding said sections and underlying the strips, the casing having a slot through which the shank of the eye projects loosely. 105

In testimony whereof, I affix my signature, in the presence of two witnesses.

HENRY W. SCHWARZ.
